HEAT EXCHANGER

Alfred Schack, Dusseldorf-Oberkassel, Germany,
assignor to Rekuperator, Gesellschaft mit
beschränkter Haftung, Dusseldorf, Germany

Application August 6, 1932, Serial No. 627,764
In Germany August 22, 1931

2 Claims. (Cl. 257—241)

The principal problem connected with the construction of heat exchangers for high temperatures consists in reducing the temperature of the highly heated parts of the surfaces of the heat exchangers to as low a degree as possible. This is most effectively carried out by increasing the co-efficient of heat transmission of the heat absorbing medium.

According to the invention such an increase 10 in the co-efficient of heat transmission is obtained without any special auxiliary agent (which always acts as a pressure absorber) by utilizing the impact effect of the heat absorbing medium which may leave the actual heating surface at a great speed.

This positive impact effect has not hitherto been useful as protection for the heating surface for the reason that the surfaces impinged upon by the heat-absorbing medium do not form 20 the part of the surface most highly heated, but are for the most part or even entirely out of the zone of action of the heating gases or of the radiation of these gases.

According to the invention the stream of the 25 heat absorbing medium impinges upon those parts of the heating surface of the preheater which are endangered either by the high temperature of the heating medium or by their small resistance to heat. Such danger exists 30 principally in the neighbourhood of those parts of the heating surface of, for example, steel recuperators which are first impinged upon by the stream of heating gas and which at the same time are exposed to the radiation of the walls 35 of the heating gas supply channel or heating chamber.

It is not essential where the temperature is 40 high that the part of the wall that is to be protected should be actually impinged by the stream of heat absorbing medium; if, for example, the part of the heating surface endangered is the wall of a channel it is sufficient 45 if one of the other walls of the channel be cooled by impact action: the wall endangered which is not directly impinged upon by the heat absorbing medium gives up so much heat to the cooled wall by radiation, when the temperatures 50 are high, that the action is almost as if the wall were itself cooled by impinging action.

The accompanying drawing illustrates dia- 55 grammatically by way of example some methods of carrying out the invention.

Figure 1 is a sectional elevation of part of a 55 heat exchanger provided with tubular elements.

Figure 1^a is a cross-section on the line 1^a—1^a of Figure 1.

Figure 2 is a sectional elevation of part of a heat exchanger provided with plate elements.

Figure 2^a is a cross-section taken on the line 60 2^a—2^a of Figure 2.

Figure 2^b is a plan view taken on the line 65 2^b—2^b of Figure 2.

Figure 3 is a sectional elevation of a modified form of heat exchanger provided with plate ele- 65

ments.

Figure 3^a is a cross-section on the line 3^a—3^a of Figure 3.

In Figure 1 the medium to be heated (air or 70 the like) is passed through the tubes 1 in the direction indicated by the arrow; these tubes open into a collecting chamber 2 from which the medium to be heated is withdrawn through the pipe 3 and conveyed to the place where it is to be used.

The collecting chamber 2 in the chamber 4 through which the stream of heating gas flows is so disposed that its walls, particularly the upright wall 5, is traversed by the stream of heating gas before the latter flows past the tubes 1 80 in parallel streams. The already heated stream of the heat-absorbing medium impinges upon the wall 5 on the inside as it is deflected into the channel 3, whereby as hereinbefore described, a large co-efficient of heat transmission 85 is obtained which reduces the temperature of the wall and in addition, by reason of the considerable withdrawal of heat, reduces the temperature of the stream of heating gas so that the stress on the tubes 1 is reduced without heat 90 being lost for heating purposes.

Similar conditions prevail in the heat exchanger illustrated in Figure 2, which is shown as a plate exchanger. The heating elements, which are formed from plates 6, connect at the end 95 7 into collecting chambers 8, the walls 9 of which are exposed to the stream of heating gas and on which the heated stream impinges on the inside and is deflected. The collecting chambers 8 are in communication with one another by means 100 of a transversely disposed channel 10, the outer wall of which is first completely or partly passed over by the stream of heating gas before it meets the surfaces 9. The heat-absorbing medium impinges upon the inner wall of the 105 channel 10 and this very considerably assists to secure the desired effect.

Figure 3 illustrates an example of the case hereinbefore mentioned of indirect cooling by impingement. The wall 12 is cooled by impinge- 110

ment, while the wall 11 is endangered by the too intense transmission of heat from without. Notwithstanding this, when the temperatures are high, the impinging action exerted on the 5 wall 12 produces an effective cooling of the wall 11, as the wall 11 radiates its heat to the wall 12 to such an extent that its temperature cannot rise much above that of the wall 12.

I claim:

- 10 1. A heat exchanger for heating gases, comprising a plurality of parallel conduits formed between the plates, a header at the delivery end of each conduit receiving the gas to be heated from the said conduit, and a delivery 15 pipe at the one end of and connecting the said headers, the heating gases of highest tempera-

ture being caused to flow transversely over the surface of the delivery pipe and over and between the surfaces of the said headers, the said surfaces being cooled by the impinging thereon of the gases to be heated as they are diverted on impinging upon the inner side of the said surfaces of the headers and upon the inner surface of the said delivery pipe.

80

2. A heat exchanger for heating gases, according to claim 1, in which the surfaces of the delivery pipe over which flows the heating gases of highest temperature, are cooled by radiation to those parts of the surface of the delivery pipe upon which the gases being heated impinge as they leave the headers.
